EYE-SHADE AND EAR-PLUG DEVICE

William F. Enright, 5220 S. Harper Ave., Apt. 108,
Chicago, Ill.

Filed Oct. 31, 1957, Ser. No. 693,759

3 Claims. (Cl. 2—15)

This invention relates generally to an eye-shade and ear-plug device, and more specifically to an improved efficient comfortable device of this type.

Although the principles of this invention may be included in various devices of this type, a particularly useful embodiment is made from a blank of silk cloth, such as a silk handkerchief. The device is used to close out light and noise from a person, such as one who is sleeping, napping, or resting. Devices heretofore used have been uncomfortable to the user, particularly as he changes position and especially when he takes a position such that his head rests on some portion of the device.

The invention comprises a pair of eye blinder portions which are preferably comprised of a single piece of soft material bunched to afford several loose layers for overlying the eyes and separated by a nose-bridge overlying contraction. At the remote ends of the eye overlying portions are provided generally strand-like portions that are of a length sufficient to be looped over the ears and which terminate in ear-plugging knob like extremities. The attachment strand portions may comprise integral extensions from the eye covering portions held by a loop stitch arrangement and the ear-plugs may be provided with a soft flocculent fill such as cotton.

Accordingly, it is an object of this invention to provide an eye-shade and ear-plug device which is comfortable to the wearer.

Another object of this invention is to provide an eye-shade and ear-plug device which uses only soft material in its structure.

A still further object of the instant invention is the provision of an eye-shade and ear-plug device wherein no elastic is used to retain the device on the head of the wearer.

Many other advantages, features and additional objects of the present invention will become manifest to those versed in the art upon making reference to the detailed description and the accompanying sheet of drawings in which a preferred structural embodiment incorporating the principles of the present invention is shown by way of illustrative example.

On the drawings:

Figure 1 is a perspective view of the device showing how the device is worn by the wearer.

Figure 2 is a plan view of a blank from which the device may be made;

Figure 3 is an enlarged plan view of the device made from the blank of Figure 2; and

Figure 4 is a further enlarged view of a fragmentary portion of Figure 3.

As shown on the drawings:

The principles of this invention are particularly useful when embodied in an eye-shade and ear-plug device such as illustrated in Figure 1, generally indicated by the numeral 10. The device includes an eye-shading portion 11 having a centrally disposed nose-bridge 12, a pair of elongated supporting members 13, 13 and an ear-plug

2

14 disposed at the outer end of the supporting members 13.

The device may be made from a unitary blank of soft material such as shown in Figure 2. I have found that silk cloth comprises an excellent material. The blank 5 of Figure 2 thus may comprise a piece of cloth similar to a handkerchief about 16" square, for example. It is not essential, however, that the blank be square. Where the material is thin, there is an advantage to the use of a square blank in that the blank may be folded along the 10 line 15 to form a triangular blank having a plurality of layers of material.

The device of Figure 3 may be made from the blank of Figure 2 as follows: the blank is centrally contracted along a line running approximately through the center 15 of the blank. This line may be one which extends from the corner 16 to the corner 16a. When the material has been gathered together, it is secured in any convenient means, such as by tying with a string or thread to define the nose-bridge portion 12. The material at the corners 20 17 and 18 is gathered together or bunched and secured as by tying or sewing to produce an enlarged portion at both ends to define the ear-plugs 14 disposed at the outer ends of the supporting portions 13. Beginning at the ear-plugs 14, the material adjacent thereto may be secured as by 25 tying together with a loop stitch to form the supporting portions or members 13 having a generally circular section and of serpentine configuration. This configuration extends from the ear-plugs 14 to a point intermediate the plug and the nose-bridge portion 12 to thereby define 30 the eye-shade portions 11.

It is to be understood that the nose-bridge portion 12 may be omitted. However, it is preferable to include this feature so that the material does not interfere with the mouth or the breathing of the wearer.

35 While the instant structure has shown the various components to be integral with each other, it is to be understood that this invention may also be practiced to advantage by employing either or both non-integral supporting members 13 and ear-plugs 14.

40 Whether the ear-plugs 14 be integral with the supporting member 13 or not, the plugs 14 may be filled with a soft material such as cotton as a means for producing the enlargement at the end without including an excessive amount of the material from the blank.

45 Referring to Figure 4, I have found that the use of the loop stitch 20 is of particular advantage in that it not only creates a circular section for the supporting member 13, but also may be used to give the supporting member 13 a natural curving or serpentine configuration. This 50 is done by providing a stitch length slightly shorter than the adjacent increment of supporting member, whereby the supporting member curves toward the axially extending portions of the stitches, as best seen in Figure 4. Further, this stitch provides a minimum of resistance to twisting 55 forces which may be imparted about the axis of the supporting member 13.

When the device shown in Figure 2 is used, it is placed on the head of the wearer as shown in Figure 1. Thus, the eye-shade portion 11 is placed over the eye to thereby reduce the amount of light which may reach the eye. The supporting member 13 circles around the back of the outer ear 30, is looped under the ear lobe 31 and extends between the tragus 32 and the antitragus 33. Thus, the supporting member 13 at its free or distal end extends 65 through the intertragial groove of the ear. The ear plug 14 is thus inserted into the concha 34 of the outer ear to block off the passage of sound waves to the inner ear. The ear-plug 14 also engages the inner surfaces of the tragus 32 and the antitragus 33 to resist disengagement 70 thereof. The cotton or similar material in the ear-plug 14 also is effective to absorb sound waves, to further in-

crease the efficiency of the device. The loop stitch 20 is effective to give the supporting member 13 a natural configuration which conforms around the outer ear, the tendency for the supporting member to further curve or straighten out being thereby minimized for increasing the comfort of the wearer.

Thus, it can be seen that a device has been provided which is an improvement over other known devices of this type. Further, it is not only more efficient, but somewhat more comfortable for the user, even though he may be partly laying on the device. Further, by the elimination of hard materials and elastic, the objective of increased comfort has been further attained.

Although various minor modifications might be suggested by those versed in the art, it should be understood that I wish to embody within the scope of the patent warranted hereon all such embodiments as reasonably and properly come within the scope of my contribution to the art.

I claim as my invention:

1. An eye-shade and ear-plug device comprising: an eye-shading portion comprising part of a unitary triangular blank of at least one thickness of soft cloth, said portion having a nose-bridge defined by a centrally gathered part of said triangular blank including a corner of said triangular blank; a pair of supporting members integrally attached to the ends of said shading portion respectively and terminating at the other corners of said blank; and a generally spherical ear plug integral with each of said supporting members, each of said plugs comprising said cloth at one of said other corners of said blank.

2. An eye-shade and ear-plug device comprising: a blank originally comprising a generally triangular configuration of a plurality of layers of soft cloth, said

5 10 15 device having an eye shading portion comprising part of said blank, said portion having a nose-bridge defined by a centrally gathered part of said triangular blank including a corner of said triangular blank; a pair of supporting members integrally attached to the ends of said shading portion respectively and terminating at the other corners of said triangular blank; and a generally spherical ear plug integral with each of said supporting members, each of said plugs comprising said cloth at one of said other corners of said triangular blank.

3. An eye-shade and ear-plug device comprising: a blank originally comprising a generally triangular configuration of a plurality of layers of soft cloth, said device having an eye-shading portion comprising part of said blank, said portion having a nose-bridge defined by a centrally gathered part of said triangular blank including a corner of said triangular blank; a pair of supporting members integrally attached to the ends of said shading portion respectively and terminating at the other corners of said triangular blank, said supporting members each comprising portions of said blank secured by a loop-stitch into a resilient normally serpentine configuration; and a generally spherical ear plug integral with each of said supporting members, each of said plugs comprising said cloth at one end of said other corners of said triangular blank.
